United States Patent Office

Des. 196,053
Patented Aug. 20, 1963

196,053

VANITY

Bertha E. Rowell, 902 W. Santa Barbara Blvd.,
Los Angeles, Calif.

Filed Aug. 26, 1960, Ser. No. 61,910

Term of patent 14 years

(Cl. D33—6)

FIG.1

FIG.2

FIG. 3

FIG. 4

FIG. 5

FIG. 1 is a perspective view of a vanity, showing my new design;

FIG. 2 is a top plan view thereof;

FIG. 3 is a front elevational view thereof;

FIG. 4 is a side elevational view thereof;

FIG. 5 is a rear elevational view thereof.

The dominant portions of my design are shown in full lines on the drawings.

I claim:

The ornamental design for a vanity, as shown and described.
